UNITED STATES PATENT OFFICE.

CARL H. ZWERMANN, OF KALAMAZOO, MICHIGAN.

SHEET-METAL TANK.

No. 921,780.

Specification of Letters Patent.

Patented May 18, 1909.

Application filed September 18, 1907. Serial No. 393,442.

To all whom it may concern:

Be it known that I, CARL H. ZWERMANN, a citizen of the United States, residing at the city of Kalamazoo, county of Kalamazoo, 5 and State of Michigan, have invented certain new and useful Improvements in Sheet-Metal Tanks, of which the following is a specification.

This invention relates to improvements in 10 sheet metal tanks for use as closet tanks or for similar purposes.

The main objects of this invention are: first, to provide an improved construction of tank formed of sheet metal, in which the 15 joint of the parts of which it is made may be enameled satisfactorily without danger of breaking the enamel, either during the enameling process or when the tank is in use; and second, to provide an improved construction of tank in which the expansion and 20 contraction of the metal, due to the heat of the enameling process, will not rupture the joints or break the enamel.

Further objects, and objects relating to 25 details of construction, will definitely appear from the detailed description to follow.

I accomplish the objects of my invention by the devices and means described in the following specification.

30 The invention is clearly defined and pointed out in the claims.

A structure embodying the features of my invention is clearly illustrated in the accompanying drawing forming a part of this specification, in which:

Figure 1 is a front elevation of a tank embodying the features of my invention, a portion being broken away to show the structural details; Fig. 2 is a plan view of my improved tank, with a portion of the cover 40 broken away; Fig. 3 is an inverted or bottom view of my improved tank; Fig. 4 is a rear view thereof; Fig. 5 is an enlarged detail taken on a line corresponding to line 5—5 of Fig. 4, showing the means for making the rear or back wall rigid so that it is not likely to buckle in enameling the same; Fig. 6 is an enlarged detail, taken on lines 6—6 of Fig. 4, showing the joint for the rear walls to the top, 45 bottom and side walls; and Fig. 7 is a detail view showing the metal somewhat exaggerated prior to the welding of the rear wall to the top, bottom and side walls.

In the drawing, similar numerals of reference refer to similar parts throughout the several views.

In the welding of sheet metal, serious difficulties are encountered. In the matter of welding by electricity, or the electric arc, a perfect weld is accomplished only in a very small area, and the parts have only been successfully welded by a butt or upset weld. It is, however, possible to weld by a blow-pipe process, by bringing the edges of the metal together in various ways; but, under such circumstances, there are likely to be crevices between the parts where they are brought together at an acute angle. These crevices cannot be cleaned by the pickle used in removing scale and rust preparatory to enameling, and unless the metal is perfectly clean of scale or rust, or if there is any surface that is not bright and clean, the enamel will not properly adhere to it. It soon peels off and opens up; and, as the enamel itself is very fragile, there is soon a crack or break through the same to the metal, which quickly rusts and the whole enameled article is destroyed. This matter of rusting is of course more likely to occur in such an article as a closet tank, as the same is constantly exposed to the action of water.

It is the main object of this invention to produce a tank made up of sheet metal in which the parts can be welded together and to avoid any narrow crevices or cracks that cannot be properly cleaned to receive the enamel; and also to produce a structure which will not warp and become injured by the heat incident to the enameling process.

In the structure illustrated, the front wall 1, the side walls 2, the bottom 3, and the top 4, are formed of a single piece of metal, the same being died or punched up, with rounded corners, so that the metal is not materially weakened in this process. As tanks of this construction are comparatively narrow from front to rear, this punching out from a single piece can be readily accomplished. The top wall 4 is punched out to form a suitable opening and the cover flange 5 is formed therein. A suitable cover, as 11, also formed from sheet metal, is provided. The rear wall 6 is preferably provided with diagonal corrugations or ribs 7 which serve to strengthen the same so that buckling is prevented during the enameling process. The back 6 is provided with a rearwardly projecting flange 8 at its edges, the flange being adapted to fit within the top, bottom and side walls. This flange 8 is curved and is provided with an upset portion 9, the face of which is substan-

tially parallel with and fits against the top, bottom and side walls, as clearly appears in Fig. 7, the upset portion from the flange being illustrated at 10. This forms a comparatively broad notch between the rear wall and its meeting walls, as clearly appears from the drawing. The rear wall is welded to its meeting walls by a hydrogen blow-pipe which is applied to the edge of the metal, and welds 5 the same into the form appearing in Fig. 6. After the rear wall is welded to the top, bottom and side walls, as described, the tank is treated to the usual pickle for removing the scale and rust, and is then suitably cleaned 10 and a coating of enamel, as 12, is applied on the inside; and, owing to the fact that there are no narrow crevices in the meeting edges of the walls, the enamel flows into the joint and perfectly contacts with and adheres 15 thereto, the joint being sufficiently wide to allow a considerable quantity to flow into the same. The advantage of this form of joint is that, owing to the curve of the joint flange, any expansion or contraction in the heating 20 process is taken up thereby, so that the joint is not affected. The joints for the bottom front wall to the side, top, and bottom, being curved, they are in the most desirable form 25 to receive the enamel.

30 I preferably provide the structure with an outer coating 13. Apertures 14 and 15 are provided in the bottom wall to receive the supply and discharge pipes, and in the rear walls are openings 16 for the purpose of se- 35 curing the tank to the wall or support; and in the front wall is an opening 17 to receive the operating mechanism. These apertures are formed prior to the enameling process, so that there are no exposed edges of the bare 40 metal.

Having thus described my invention, what I claim as new and desire to secure by Letters Patent is:

1. A sheet metal tank comprising front, 45 side, top and bottom walls, formed from a single piece of sheet metal, the top wall having a cover-opening therethrough, the said opening being provided with an upwardly projecting flange at its edges, adapted to receive the cover; a rear wall having diagonal corrugations therein, said rear wall being provided with an outwardly-projecting curved flange at its edges, the edge of said flange 50 being offset and substantially parallel to the edge portion of the bottom, top and side walls into which it is fitted and to which it is joined by welding, there being a notch at the joint; and an interior coating of enamel 55 extending into said notch, as specified.

60 2. A sheet metal tank comprising front, side, top and bottom walls formed from a single piece of sheet metal; a rear wall having diagonal corrugations therein, said rear wall being provided with an outwardly-projecting curved flange at its edges, the edge of 65

said flange being offset and substantially parallel to the edge portion of the bottom, top, and side walls into which it is fitted and to which it is joined by welding, there being a notch at the joint; and an interior coating of enamel, extending into said notch, as specified. 70

3. A sheet metal tank comprising front, side, top and bottom walls formed from a single piece of sheet metal, the top wall having a cover-opening therethrough, the said opening being provided with an upwardly projecting flange at its edges, adapted to receive the cover; a rear wall provided with an outwardly-projecting curved flange at its edges, 75 the edge of said flange being offset and substantially parallel to the edge portion of the bottom, top and side walls into which it is fitted and to which it is joined by welding, there being a notch at the joint; and an interior coating of enamel extending into said notch, as specified. 80

4. A sheet metal tank comprising front, side, top and bottom walls formed from a single piece of sheet metal; a rear wall provided with an outwardly-projecting curved flange at its edges, the edge of said flange being offset and substantially parallel to the edge portion of the bottom, top, and side walls into which it is fitted and to which it is 90 joined by welding, there being a notch at the joint; and an interior coating of enamel extending into said notch, as specified. 95

5. A sheet metal tank comprising front, side, top and bottom walls; a rear wall provided with an outwardly-projecting curved flange at its edges, the edge of said flange being offset and substantially parallel to the edge portion of the bottom, top and side walls into which it is fitted and to which it is 100 joined by welding, there being a notch at the joint; and an interior coating of enamel, extending into said notch, as specified. 105

6. A sheet metal tank comprising front, side, top and bottom walls, formed from a single piece of sheet metal; a rear wall provided with an outwardly-projecting curved flange at its edges, said flange being fitted into and joined at its edges to the edges of said top, bottom and side walls, by welding, 110 there being a notch at the joint; and an interior coating of enamel extending into said notch. 115

7. A sheet metal tank comprising front, side, top and bottom walls; a rear wall provided with an outwardly-projecting curved flange at its edges, said flange being fitted into and joined at its edges to the edges of the said top, bottom, and side walls, by welding, there being a notch at the joint; and an interior coating of enamel extending into 120 said notch. 125

8. A sheet metal tank comprising front, side, top and bottom walls, formed from a single piece of sheet metal; a rear wall pro- 130

vided with an outwardly-projecting curved flange at its edges, said flange being fitted into and joined at its edges to the edges of the said top, bottom and side walls, by welding, 5 there being a notch in the flange at the joint adapted to receive a coating of enamel.

9. A sheet metal tank comprising front, side, top and bottom walls, and a rear wall provided with an outwardly-projecting 10 curved flange at its edges, said flange being fitted into and joined at its edges to the edges of the said top, bottom and side walls, by welding, there being a notch in the flange at the joint adapted to receive a coating of 15 enamel.

10. A tank comprising sheet metal walls, one of which is provided with an outwardly-projecting curved flange at its edges, the outer edge of said flange being offset and substantially parallel to the meeting wall to which it is fitted and joined to said wall by welding, there being a comparatively broad notch at the joint; and an interior coating of enamel extending into said notch. 20

11. A tank comprising sheet metal walls, 25 one of which is provided with an outwardly-projecting curved flange at its edges, the outer edge of said flange being offset and substantially parallel to the meeting wall to which it is fitted and joined to said wall by 30 welding, there being a comparatively broad notch at the joint adapted to receive a coating of enamel.

12. A tank comprising sheet metal walls, 35 one of which is provided with an outwardly-projecting curved flange at its edge, said flange being joined at its edge to the edge of the meeting wall by welding, there being a comparatively broad notch at the joint; and an interior coating of enamel extending into 40 said notch.

In witness whereof, I have hereunto set my hand and seal in the presence of two witnesses.
